(57) **CLAIM**

The ornamental design for a portable wireless communication device, as shown and described.

DESCRIPTION

FIG. 1 is a front, top and left side perspective view;

FIG. 2 is a front elevation view;

FIG. 3 is a rear elevation view;

FIG. 4 is a top plan view;

FIG. 5 is a bottom plan view;

FIG. 6 is a left side elevation view; and,

FIG. 7 is a right side elevation view.

The broken lines in the drawings are for the purpose of illustrating portions of the portable wireless communication device that form no part of the claimed design.
